UNITED STATES PATENT OFFICE.

CHARLES M. FOWLER, OF MOULTRIE, GEORGIA.

SWEEP ATTACHMENT.

997,384.

Specification of Letters Patent. Patented July 11, 1911.

Application filed June 15, 1910. Serial No. 567,079.

To all whom it may concern:

Be it known that I, CHARLES M. FOWLER, a citizen of the United States, residing at Moultrie, in the county of Colquitt and State 5 of Georgia, have invented a new and useful Sweep Attachment, of which the following is a specification.

This invention relates to a sweep attachment for plows and consists in the novel construction and arrangement of its parts as 10 hereinafter shown and described.

The object of the invention is to provide an attachment adapted to be applied to a plow stock and includes a clamping means 15 adapted to adjustably hold sweep blades whereby the said blades may be disposed at any desired angle with relation to the surface of the soil.

In the accompanying drawing:—Figure 1 20 is a side elevation of a plow with parts in section showing the sweep attachment applied thereto. Fig. 2 is a top plan view of the sweep attachment detached. Fig. 3 is an edge elevation of the attachment detached. Fig. 4 is a plan view of the attachment with one of the clamping members removed.

The sweep attachment consists of clamp blocks 1 and 2 which are provided at their 25 side edges with semi-globular sockets 3. A heel bolt 4 passes transversely through the blocks 1 and 2 and also serves as means for securing the plow point 5 in position upon the lower end of a plow standard 6 in the 30 manner as indicated in Fig. 1 of the drawing. A supplemental bolt 7 also passes transversely through the said blocks 1 and 2 and serves as additional means for holding the said blocks. Ledger plates 8 are 35 provided with bearing faces and globular heads 9 which extend at obtuse angles to the bearing faces of the plates and which are adapted to be secured in the sockets 3 at the sides of the blocks 1 and 2 and upon the bearing face of 40 each ledger plate 8 is mounted a scraper blade 10. By this structure it will be seen that a ball and socket connection is established between the ledger plates and the 45 clamp blocks 1 and 2 and that by loosening the bolts 4 and 7 the scraper blades 10 may be pitched at any desired angle with relation to the surface of the soil and after being 50 properly adjusted are secured in adjusted position by tightening the said bolts 4 and 7.

By such an arrangement an attachment of 55 simple structure is provided which may be easily and quickly detached from the standard of a plow and in which the scraper blade may be quickly and securely held at any desired angle as indicated. 60

Having described the invention, what I claim as new and desire to secure by Letters Patent is:—

1. The combination with a plow standard and a plow point attached thereto, a bolt 65 passing through the point and standard and projecting to the rear thereof, of a sweep attachment, comprising two co-acting clamping plates provided with two apertures, one to receive the projecting end of 70 the bolt and with two sockets upon opposed faces forming when the plates are in opposed position two globular receptacles, two ledger plates, each one provided with a globular head adapted to fit in the respective 75 socket of the clamping plates and to normally hold the plates slightly apart when the plates are holding the ledger plates in adjusted position, a short bolt passing through the other opening of the plate, and 80 nuts upon the outer ends of the bolts for clamping the ledger plates in adjusted position and simultaneously locking the plow point to the standard. 85

2. A sweep attachment, comprising two 85 plates, said plates being provided with semi-spherical depressions or recesses intermediate of its ends near the long edges thereof, two ledger plates, a scraper blade carried by each ledger plate, a cylindrical stem carried 90 by each ledger plate, and a globular head forming the terminal for each stem, the globular heads of the ledger plates being adapted to fit within opposed recesses of the plates, and means for clamping the plates 95 toward each other to hold the globular heads of the ledger plates in adjusted position, whereby said ledger plates may be adjusted to various angles with relation to each other. 100

In testimony that I claim the foregoing as my own, I have hereto affixed my signature in the presence of two witnesses.

CHARLES M. FOWLER.
